(57) **CLAIM**

I claim the ornamental design for an erasable jotting pad with pressure adhesive for attaching to tape measure, as shown and described.

DESCRIPTION

FIG. 1 is a perspective view of an erasable jotting pad with pressure adhesive for attaching to tape measure showing my new design in use; the broken lines depict environmental structure for illustrative purposes only and form no part of the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
